CLAIM

The ornamental design for a remotely controlled curtain positioner cover, as shown and described.

DESCRIPTION

FIG. 1 is a front perspective view of a remotely controlled curtain positioner cover showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a end elevational view thereof; and,

FIG. 7 is an opposite end elevational view thereof.

The cord is shown fragmentarily for convenience of illustration.
